ATTORNEYS

UNITED STATES PATENT OFFICE.

NATHANIEL LYKE, OF JAMESTOWN, NEW YORK.

SINK-STRAINER.

No. 852,233.

Specification of Letters Patent.

Patented April 30, 1907.

Application filed March 8, 1906. Serial No. 304,983.

To all whom it may concern:

Be it known that I, NATHANIEL LYKE, a citizen of the United States, residing at Hotel Everett, Jamestown, in the county of Chautauqua and State of New York, have invented a new and useful Sink-Strainer, of which the following is a specification.

This invention relates to removable strainers employed in sinks and similar structures for retaining the coarser particles of material and permitting the liquids only to pass through, and has for its object to improve the construction and increase the efficiency and utility of devices of this character.

With this and other objects in view which will appear as the nature of the invention is better understood, the invention consists in certain novel features of construction as hereafter fully described and claimed.

In the accompanying drawings forming a part of this specification and in which corresponding parts are denoted by like designating characters, is illustrated the preferred form of the embodiment of the invention capable of carrying the same into practical operation.

Figure 1 is a perspective view of the improved device. Fig. 2 is a perspective view of one of the end frames from the inside. Fig. 3 is a view of one of the blanks from which the end frames are formed.

The improved device comprises a body 10 of foraminous material, preferably perforated metal, or which may be of wire screen material, of relatively fine mesh.

The body portion is preferably formed with flaring sides and rounded at the bottom, and with the ends likewise of perforated material. The body thus constructed is supported at the ends by frames, each formed from a single sheet of metal extending at 11 below the bottom of the body and with branches 12-13 extending therefrom and flaring outwardly in conformity to the flaring sides of the body, and bent around the corners of the same, to form bindings to the body at the corners. The depending portions 11 are strengthened and supported by folding the edges over upon themselves as at 14.

Bearing over the upper edges of the body

portion are binder strips 15, embracing both the upper edges of the body portion and the upper ends of the corner binding members 12-13, all the parts being firmly secured by 55 soldering or otherwise. A lift ring 16 is attached to one end of the device.

It will be noted that a very strong compact and durable device is produced, which is firmly supported by the end frames and 60 the bottom portion maintained spaced above the structure on which the device rests, as for instance the bottom of the sink in which it is disposed, to provide for adequate drainage and prevent the clogging of the body. 65

The inclined sides and the rounded bottom of the body portion renders the device easily cleaned, and effectually prevents the particles retained therein from lodging against the interior of the body. 70

The device may be constructed of any size to correspond to the sink or other receptacle in which it is employed.

What I claim is:—

1. A strainer having a body of perforated 75 material and supported at the ends by frames, each frame formed from a single piece of sheet metal extending below the body and having integral branches bent around the corners of the same, the extended 80 portions being reinforced by bending the metal at the edge upon itself.

2. A strainer having a body of perforated material and supported at the ends by frames, each frame formed from a single 85 piece of sheet metal extending below the body and having integral branches bent around the corners of the same, the extended portions being reinforced by bending the metal at the edges upon itself, and binding 90 strips of sheet metal folded longitudinally upon themselves and bearing over the upper edges of the body and the upper ends of the bent corner supporting branches.

In testimony that I claim the foregoing as 95 my own, I have hereto affixed my signature in the presence of two witnesses:

NATHANIEL LYKE.
